UNITED STATES PATENT OFFICE.

ASA B. SUESMAN, OF SPRINGFIELD, MASSACHUSETTS.

GOLF-CLUB.

1,305,952.

Specification of Letters Patent. Patented June 3, 1919.

Application filed March 31, 1917. Serial No. 159,008.

To all whom it may concern:

Be it known that I, ASA B. SUESMAN, a citizen of the United States of America, and resident of Springfield, in the county of 5 Hampden and State of Massachusetts, have invented certain new and useful Improvements in Golf-Clubs, of which the following is a full, clear, and exact description.

This invention relates to improvements in 10 golf-clubs, and more particularly to the grip portion thereof.

The success of a golf stroke depends largely upon the manner in which the club 15 is gripped with the hands. It is the almost universal practice to employ the left hand above the right in making a shot; and if the left hand grasps the club too tightly, the ball has a tendency to swerve to the right, and a 20 too tight grip by the other hand causes the ball to go to the left of the direction aimed at.

This invention is based on the idea that if the portion of the club to be gripped by one of the hands is so made that it can revolve on the shaft, the liability of making a faulty 25 stroke will be greatly lessened. For instance, if the player is in the habit of grasping the club too hard with his left hand, this fault will be diminished if the upper part of the 30 portion of the club to be grasped is made with the capability of revolving on the shaft for the reason that the left hand is thereby deprived of the power to twist the club out of its best operative position.

An exemplification of the invention as it 35 has been successfully carried out is herein-after described in connection with the accompanying drawings and is covered by the claims.

In the drawings:

40 Figure 1 is a side view showing a golf club comprising the invention.

Fig. 2 is a longitudinal sectional view of the portion of the club at which the device of this invention is provided.

45 Fig. 3 is a partial longitudinal sectional view showing a modification to be herein-after referred to.

In the drawings, A represents the shaft of a golf club of which B and C are the grips 50 or upper portions of the shaft to be grasped by the player.

The lower grip portion B is, as here represented, understood to be fixedly provided or immovable on or relatively to the shaft, 55 while the upper grip portion C is freely rotatable about the shaft, being made as an

elongated sleeve or ferrule and of any suitable material or combinations of material.

This grip may consist of a metallic tube a of circular cross section and to loosely fit 60 about the round portion of the shaft which is encircled thereby; and provided with a covering or wrapping b of suitable material, such, for instance, as leather.

A metallic washer d is provided to encircle 65 the shaft at the upper end of the fixed grip member B and on which the lower end of the revoluble grip member C may rest; and a short sleeve section or ferrule f is shown as fastened by the pin g about the upper end 70 of the shaft and forms a limiting shoulder for the revoluble grip for the prevention of the latter from displacement from the shaft.

Inasmuch as it may be desired to render the golf club one in which the revoluble grip 75 thereof is convertible into a fixed grip, to be one of that nature temporarily or otherwise, I have shown in Fig. 3 one of various expedients which may be resorted to to this end, that is providing external screw threads 80 h on the shaft and providing a binding nut i and a thumb nut j between the end of the revoluble grip and the shoulder forming ferrule f.

When the nuts are loose relatively to the 85 end of the grip, the latter may freely revolve, while on the other hand the turning down of the nuts will be effective to firmly bind the grip against rotation or other movement relatively to the stick.

Inversion or reversal of the relations of the grip members may be made within the scope of this invention as also various changes as to details of construction may be made without departing from or sacrificing any of the advantages of the invention.

I claim:

1. A golf club having at the upper portion of the shaft a grip member which is revoluble relatively to the shaft.

2. A golf stick comprising a shaft having a striking member on one end thereof and a pair of hand grips on the opposite end thereof, said hand grips being longitudinally spaced from each other on said shaft, the upper one of said hand grips being mounted on said shaft for rotary movement and the other of said hand grips being fixed to the shaft against relative movement thereon, one of said hand grips being designed to be grasped by the right hand of the player and the other of said grips being designed to be

grasped by the left hand of the player, whereby the pressure exerted by the player's hands will be somewhat balanced on said shaft.

5. 3. A golf club including a continuous shaft and grip for golf clubs comprising a section fast to the club shaft and an adjacent section capable of revoluble movement with respect to the shaft.

10. 4. A grip for golf clubs comprising a sec-

tion fast to the club shaft, an adjacent section revolubly mounted on said shaft, and means to confine said revoluble section against longitudinal movement on the shaft.

Signed by me at Springfield, Mass., in 15 presence of a subscribing witness.

ASA B. SUESMAN.

Witness:

G. R. DRISCOLL.
